JOHN B. EHRLICH, OF PORTLAND, OREGON

STOKER

Original application filed January 30, 1928, Serial No. 250,518. Divided and this application filed February 20, 1929. Serial No. 341,551.

This application is a division of the applicant's co-pending application Serial No. 250,518.

This invention relates generally to stokers for burning cut fuel, and particularly to a special form of stoker adaptable to industrial purposes.

The first object of this invention is to provide a stoker which will secure the most complete combustion possible.

The second object is to adapt the stoker to all kinds of solid fuel in cut or crushed form.

The third object is to provide a stoker having a special form of self-cooling grate bar, and having means for varying the path of the burning gases from the time they are generated until the time they pass beyond the grates.

The fourth object is to provide a grate whose individual units are rotatable with relation to each other and are so arranged as to cause an undulating motion to the fuel as it passes over the grates.

The fifth object is to so construct the grates of the stoker that air passing through same shall be warmed and distributed in a manner to provide a flow of air to the various grate areas best adapted for complete combustion of the fuel.

These, and other objects, will become more apparent from the specification following as illustrated in the accompanying drawings, in which:

Figure 1 is a longitudinal section through a form of the device as applied to an industrial boiler. Figure 2 is a fragmentary section taken along the line 2-2 in Figure 3. Figure 3 is a section taken along the line 3-3 in Figure 1. Figure 4 is an enlarged fragmentary section taken along the line 10-10 in Figure 1. Figure 5 is a section taken along the line 5-5 in Figure 3.

Similar numbers of reference refer to similar parts throughout the several views.

Referring in detail to the drawings, there is illustrated a common form of boiler having the tubes 79 at whose forward end is positioned the boiler front 80 of brickwork, in which is formed a fire door opening 81 and an ash pit door opening 82. A bridge

wall 83 extends across the boiler a short distance from the rear wall 84. The relation, shape and size of these elements will vary considerably with different installations.

The device itself consists of two main elements, namely a special form of grate and an air preheating device. The grate includes a pair of hollow side frames 85 which are placed close to the side walls 86 of the boiler which are supported at their rearward ends 55 in the bridge wall 83 and at their forward ends in the boiler front 80, the front being somewhat higher than the rear. Midway between the side frames 85 is a U-shaped center frame 87 in which is mounted a plurality of sprocket wheels 88 having round hubs 89 which journal in the frame 87, which hubs have square extensions 90 formed thereon which fit into square openings in the grate bars 47. The opposite end of each bar 60 47 is mounted on the square end 91 of the trunnion 92 of the cam 93 upon which rides an arm 94 of the cover plate 95 which serves 65 as a closure for the open top side of the frame 85.

The frames 85 are also provided with air outlet openings 96 at the lower portion thereof of which discharge air beneath the under side of the grate bars 47. The sprockets 88 also have formed thereon the cam surfaces 97 upon 70 which ride the arms 98 which support the double sloping angle bar 99 which form a closure for the top side of the frame 87.

In front of the furnace is placed a motor 100 from which is driven a blower 101 which 75 delivers air through the duct 102 into the manifold 103 over the bridge wall 83. From the manifold 103 extend branches 104 which connect with the rearmost ends of the frames 85 and 87 by means of which heated air from the manifold 103 can be delivered into the combustion chamber, either through the grate bar openings 48, or in reversing directions from the frames 85 or 87. By that is 80 meant that the cams are so timed that when the member 99 is up (as shown in Figure 3) then the members 95 are down, and vice versa, thereby securing repeated reversals in the 85 direction of flow of air across the grates. 103

It is of course understood that the members 95 and 99 may be sectional (as shown in Figure 1) and that only enough of the arms 94 and 98 are needed to properly operate same.

5 Fuel is supplied to the device from a magazine 105 which is hinged on a pivot 106 on the front 107 of the boiler. A door 108 is provided at the outlet of the fuel magazine for controlling the supply of fuel to the grates. It is of course obvious that fuel may be supplied to the magazine 105 by a chute 109, or in any other convenient manner. Rotation is supplied to the grate bars 47 by 15 means of a chain 110 which is driven from a reduction gear 111, and, in turn, through the sprocket wheel 112 on the countershaft 113, which sprocket wheel drives the chain 114 around the idler sprocket wheels 115 and the 20 various sprocket wheels 88 of the grate bars 47. Each grate bar 47 is provided with openings 48 in the flat sides thereof and has a plurality of encircling flanges 49 disposed along the length of each bar in alternate fashion—that is, the flanges of one bar will be intermediate to the flanges of the adjacent bars.

25 It will be noted that fuel is admitted to the combustion zone in a relatively flat layer which moves along the grates in undulating or wave-like form, due to the fact that the hexagonal grate bars 47 are alternately positioned so that the corners of one set of bars are up while the flat sides of the intermediate bars are up, thereby not only providing a 30 continuous feed of fuel through the furnace, but also providing a thorough and constant agitation for the fuel.

35 In addition to this ideal condition for fuel feeding it will be seen that there is also provided a means for preheating the air used in the combustion, which air is also used to protect the grate bars 47 from over-heating.

40 In the ordinary form of chain grate a given section of metal remains exposed to the cold throughout its travel along the top side of the grate and cools off on the under side. Obviously, the time during which it is exposed to heat is often sufficient to bring about the 45 destruction of the grate. Whereas in the device herein described the portion of the grate exposed to the heat is constantly being turned away therefrom and air is permitted to flow through the hollow grates, thereby further protecting same.

45 In the type of furnace shown herein there is a constant reversal in the air flow affected by means of the members 95 and 99, one instant flowing toward the center of the furnace and the next instant flowing toward the other 50 sides thereof, thereby securing a complete mixing of the gases and uniform distribution of the heat developed within the combustion chamber. Obviously, the supply of air delivered to the combustion can be easily controlled at the blower 101, and the amount of

fuel consumed can be controlled by the position of the door 108.

I am aware that many forms of furnaces have been constructed for industrial purposes; it is therefore not my intention to cover such devices broadly, but I do intend to cover all such forms and modifications thereof as fall fairly within the appended claims.

I claim:

1. In a stoker the combination of a pair of spaced hollow side frames with a plurality of rolling grate bars rotatably mounted between said side frames, each of said bars having an air passage formed therethrough connecting with the interior of said side frames, each of said side frames having a cover plate over the top thereof forming a closure for the top side of its side frame, and means for alternately raising and lowering said cover plates in opposite directions for the purpose of reversing the path of the burning gases as they pass over said grates.

2. A stoker for industrial furnaces consisting of a pair of hollow side frames disposed against opposite walls of a furnace setting, an intermediate frame between said side frames, said frames sloping downwardly away from the point of fuel feeding, a plurality of rotatable hollow grates having polygonal surfaces provided with air outlets communicating with the interior thereof, means for rotating all of said grates in the same direction, an air supplying manifold communicating with each of said side frames, fan means for supplying air to said manifold, each of said side frames and intermediate frame having an air outlet along its outer side, a cover plate over each of said outlets forming a closure therefor adapted to deflect air laterally across said grates when partially raised, means for rotating all of said grates in a manner to carry fuel thereon downwardly along their sloping surface, and means for raising and lowering said cover plates successively in opposite directions in a manner that the flow of air along said grates from said frames shall be continually reversed.

3. A stoker for furnaces having a plurality of hollow rotatable grate bars forming a sloping grate area, an air-conducting frame supporting the ends of said bars having an outlet along the top side thereof through which air can escape laterally across said grates, a closure for each of said openings, and means for operating said closures alternately in a manner to successively reverse the flow of air across said grates.

JOHN B. EHRLICH. 125
